CLAIM

The ornamental design for a carrying bag for attachment to a crutch, as shown and described.

DESCRIPTION

FIG. 1 is a front elevational view, shown in reduced size showing the first embodiment of my design in a mounted position;

FIG. 2 is a front elevational view of the first embodiment of my new design;

FIG. 3 is a back elevational view thereof;

FIG. 4 is a left end elevational view thereof, in a collapsed form with the lid partially open, the opposite side being a mirror image thereof;

FIG. 5 is a left end elevational view of the first embodiment in an expanded form, with the lid closed, the opposite side being a mirror image thereof;

FIG. 6 is a perspective view of the first embodiment;

FIG. 7 is a top plan view of the first embodiment of my design;

FIG. 8 is a bottom plan view thereof;

FIG. 9 is a front elevational view of the second embodiment of my new design;

FIG. 10 is a back elevational view thereof;

FIG. 11 is a left end elevational view thereof, in a collapsed form with the lid partially open, the opposite side being a mirror image thereof;

FIG. 12 is a left end elevational view of the second embodiment in an expanded form, with the lid closed, the opposite side being a mirror image thereof;

FIG. 13 is a perspective view of the second embodiment;

FIG. 14 is a top plan view of the second embodiment of my design; and,

FIG. 15 is a bottom plan view thereof.

The broken line showing of a crutch is for illustrative purposes only and forms no part of the claimed design.
